UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

TESTING SYSTEM.

Application filed January 16, 1920. Serial No. 351,943.

To all whom it may concern:

Be it known that I, KENNETH S. JOHNSON, a citizen of the United States, residing at Jersey City, in the county of Hudson and State of New Jersey, have invented certain new and useful Improvements in Testing Systems, of which the following is a full, clear, concise, and exact description.

This invention relates to testing systems, and more particularly to systems for the testing of electric signaling and telephone systems.

The principal object of the invention is to provide a testing system in which matter being transmitted over the lines of a signaling system is not transmitted to the test observing apparatus. In accordance with this feature of the invention, means are interposed in the testing circuit which prevents the transmission of signaling current from the signaling system to the test observing or indicating apparatus while providing for the transmission of testing current thereto.

Another object of the invention is to provide a testing system which will not interfere with the transmission of signals over lines connecting two stations during testing. In accordance with this feature of the invention, the testing current applied to the lines is of such a low strength that it does not materially interfere with signaling over lines during the testing operation; the testing current being subsequently amplified to a degree such that its presence is readily detected either by an observer or by suitable automatic indicating or recording means.

Other objects and features of the invention not specifically mentioned above will be apparent in the following specification and from the appended claims.

The drawing shows diagrammatically one form of the invention as applied to a testing system for an automatic call distributing telephone system.

In this embodiment of the invention a subscriber's station A is shown in telephonic communication with station B through the medium of an automatic line finder switch LF and its associated automatic cord selector switch CS together with a cord circuit 10 with its plug 11 and the jack 12 of station B. The details of how this connection is established form no part of the present

invention and reference is made to the co-pending application Serial No. 275,074 of S. B. Williams, Jr., and H. L. Bostater, filed February 5, 1919, Patent No. 1,445,258, granted February 13, 1923, for a description thereof.

The conductors 14, 15 and 16 are those individual to another calling subscriber's station, the same as station A, and these conductors are shown as connected with conductors 17, 18 and 19 respectively of another cord circuit 20, terminating in a plug 21, through an automatic line finder LF and its associated automatic cord selector CS'. The line connected with the cord circuit 20 is intended to represent a line which has been found to be in trouble and the plug 21 is intended to be inserted into a tone jack 22 for the purpose of impressing testing current on the cord circuit and its associated apparatus to facilitate the location of the line finder involved and from this the particular line in trouble. As more fully described in the Williams-Bostater patent application previously referred to, a testing contact bank 23 is provided with a number of pairs of test terminals, each line finder having an individual pair allotted thereto and the terminals of each pair being connected to the tip and ring brushes of the brush sets of their respective line finders. The brush set 24 is designed to pass over this contact bank and to successively engage these sets of contacts. The number of the line finder whose test terminals are engaged at any time is denoted by the number on the designation strip 25 associated with the bank 23 as indicated by a pointer 26 movable with the brush set 24.

The testing contact bank 23 with its brush set 24 is preferably located at an observer's position. For testing, an observer's set 27 having its receiver 28 and transmitter 29 connected respectively between the sleeve and tip contacts of the plugs 30 and 31 is provided and in testing these plugs are inserted into the jacks 32 and 33 respectively.

A tone generator 36 is provided to supply testing current for testing operations; and a transformer 37 having a primary winding included in the output circuit of the generator 36 is also provided, the secondary winding of this transformer having one side

connected to ground while the other side is connected to a conductor extending to and connecting in multiple the tip and ring contacts of a number of tone jacks, such as the 5 jack 22 shown. The plug 21 of cord circuit 20, assuming this cord circuit to be in trouble, would have been inserted in the tone jack 22 and, accordingly, testing current would flow over two parallel circuits, one 10 extending from ground, secondary winding of transformer 37, tip contacts of jack 22 and plug 21, and upper right-hand winding of the repeating coil of cord circuit 20 to ground, while the other extends from 15 ground, secondary winding of transformer 37, resistance 38, ring contacts of jack 22 and plug 21, lower right-hand winding of the repeating coil of cord circuit 20 and the battery thereof, to ground. The current 20 flowing from ground through the upper right-hand winding of the repeating coil at cord 20 to ground in one instance, and that flowing from ground through the resistance 38 in series with battery at the 25 repeating coil at cord 20 in the other instance, produces a difference in the potentials which are induced into the left-hand windings of said coil. The generator 36 develops alternating current and the frequency thereof 30 should preferably be quite different from the frequencies of the signaling currents present on the lines when the latter are in use for signaling purposes.

In the case of testing systems for telephone lines, the frequency of the testing current is preferably below 150 cycles per second, in order that they may be readily identified by the production of a characteristic tone by the receiver 28 and also in 35 order that currents of telephonic frequencies (in practice well over 150 cycles a second) may be prevented from interfering with the testing operation. The latter feature is accomplished in the system shown on 40 the drawing by including an electrical filter comprising condensers 40 and impedance coils 41 so proportioned and arranged as to prevent the passage of electric currents of frequencies substantially over 150 cycles per 45 second being transmitted to the right-hand winding of the transformer 42. The left-hand winding of this transformer is included in the input circuit of the thermionic amplifier 43 comprising a grid 44, a filament 50 45 and a plate 46. The input circuit of this amplifier includes the left-hand winding of transformer 42, battery 47, grid 44 and filament 45 of the amplifier.

It is not desired to utilize the amplifier 55 except during testing and the energizing circuits thereof are accordingly so arranged that they are normally open; the closure thereof being controlled by the insertion of the plug 31 of the observer's set into the 60 jack 33. Upon such insertion, however, con-

tact 48 is closed, thereby completing circuits for the energization of relays 49 and 50. The operation of relay 49 completes a heating circuit for the filament 45 extending from positive side of battery 51, left-hand contact of relay 49, adjustable resistance 52, filament 45 and right-hand contact of relay 49 to the other side of battery 51. The actuation of relay 49 also cooperates 70 with relay 50 upon its operation to complete an output circuit for the amplifier 43 extending from grounded battery 53, contact of relay 50, right-hand winding of transformer 54, plate and filament of amplifier 43, right-hand contact of relay 49 and batteries 51 and 55 to ground. Battery 53 has its positive terminal grounded while the batteries 51 and 55 are connected in the above circuit in series aiding relation to battery 53; the negative side of battery 55 80 being grounded. The connection of the observer's set also completes a circuit including the left-hand winding of transformer 54, sleeve contacts of jack 33 and plug 31, receiver 28 and sleeve contacts of plug 30 85 and jack 32. No transmitting circuit is shown for the observer's set inasmuch as this feature is not essential in the particular testing system shown on the drawing.

In testing, the observer moves the brush 90 set 24 over the terminal bank 23. Assuming that the line finder (not shown) to which the lower pair of terminals is individual is not in use, no current of any sort will be 100 present upon these terminals and the engagement of the brush set 24 therewith is accordingly without effect. The terminal pair 2 belonging to a second line finder (identified as LF on the drawing) will, however, have direct current thereon from 105 the battery of the cord circuit 10 involved in the talking circuit between stations A and B; but this direct current does not affect the input circuit of the amplifier 43 upon 110 the engagement of brush set with the test terminals of this line finder due to the provision of the condenser 57 serially in the circuit between brush set 24 and the right-hand winding of the transformer 42, which 115 prevents the passage of direct current. While fluctuating currents are also present on the test terminals of line finder LF due to the fluctuating currents developed in 120 talking between stations A and B, these fluctuations are of frequencies in excess of those which the electrical filter comprising condensers 40 and impedance coils 41 is 125 designed to admit to the right-hand winding of transformer 42. Accordingly, these fluctuating voice currents are without effect on the amplifier, and thus no corresponding currents are communicated to the circuit of the receiver 28. This filtering action prevents signaling currents present on lines 130 in use when tested over being transmitted

to the observer and thus renders the detection of testing currents possible with a minimum of effort.

The flow of testing current in parallel 5 through the right-hand windings of the repeating coil in cord circuit 20 induces corresponding currents of like frequencies in the left-hand windings of this coil. Testing current is accordingly present on both tip 10 and ring conductors of the cord circuit 20, the cord selector CS', the line finder LF' and on the test terminals of this line finder in the contact bank 23. On the brush set 24 engaging these terminals, an operative 15 circuit is completed extending from grounded battery and lower left-hand winding of the repeating coil of cord circuit 20, the ring contacts of the cord circuit and brush set of cord selector CS', ring test terminal of 20 the associated line finder LF' in bank 23 and ring contact of brush set 24, right-hand winding of transformer 42, the impedance coils 41, condenser 57, tip contact of brush set and tip test terminal of the line finder 25 LF' in bank 23, tip contacts of the brush set of the cord selector CS' and cord circuit 20 and the upper left-hand winding of the repeating coil of this cord circuit to ground.

The testing current impressed upon the 30 cord circuit is preferably of low value in order to prevent the creation, due to inductive action, of correspondingly fluctuating currents of sufficient strength to interfere with efficient signaling communication over 35 neighboring cord circuits. The current flowing over the testing circuit above traced being of testing frequency (below 150 cycles per second) is freely transmitted to the right-hand winding of the transformer 42 40 by the electrical filter and in traversing this winding produces corresponding current variations in the input circuit of the amplifier 43. This amplifier in response thereto develops corresponding current fluctuations 45 of increased amplitude in the output circuit thereof which in traversing the right-hand winding of transformer 54 induce like fluctuations in the circuit including the left-hand winding of this trans- 50 former and the receiver 28 of the observer's set. These latter fluctuations are translated by the receiver 28 into sound of a frequency corresponding to that of the current developed by the testing generator 36 and the 55 production of this characteristic sound indicates to the observer that the brush set 24 is in engagement with the test terminals of the particular line finder at that time associated with the cord circuit 20 upon which 60 testing current has been impressed, as previously noted. The pointer 26 is opposite the numeral 3 on the designation strip at this time and thus indicates that line finder 3 (designated as LF' on the drawing) is the 65 one involved in the connection. Having as-

certained the particular line finder concerned, this line finder is visited and the set of line terminals thereof engaged by the brush set of the line finder noted. From this the particular line involved in the connection can be readily determined, after which such line is conditioned so as to test in trouble and the line finder LF' restored to normal position ready for subsequent use with other lines having their contacts in 75 the terminal bank of such line finder.

In the particular system illustrated, the restoration of the line finder LF' also effects the restoration of the associated cord selector CS' to normal and the operation 80 of the disconnect signal (not shown), as described in the Williams-Bostater patent application previously mentioned. The operation of this disconnect signal serves to indicate to the operator that the trouble 85 has been cleared and the operator thereupon withdraws the plug 21 from the jack 22, thus restoring the cord circuit to its normal condition ready for subsequent use. In event that other line finders connected to 90 lines in trouble are still to be located, the observer continues testing over the test bank 23 until all are identified and the apparatus associated therewith restored to normal.

On completion of testing, the observer removes the plugs 30 and 31 of his set from jacks 32 and 33, whereupon relays 49 and 50 release opening both the filament heating and the output circuits of the amplifier 43. The opening of these circuits prevents 100 drain upon the current supply sources except at such times as the system is in use for testing purposes. Upon completion of this operation by the observer, the testing system is in normal condition ready for subsequent use as occasion demands.

The arrangement herein set forth is intended as merely illustrative of the present invention, which is not limited to the precise details set forth except as required by 110 the claims forming a part hereof.

What is claimed is:

1. A testing system comprising a plurality of lines used for signaling communication, a source of fluctuating testing current 115 having a certain frequency range, means to develop signaling currents for transmission over the lines having a frequency range exclusive of that of the testing current, an electroresponsive test observing device, an 120 electrical circuit connection to associate the device with the lines to be tested, and electrical means included in such connection operable to prevent the transmission of current within the signaling frequency range to the 125 device while permitting transmission of currents within the testing frequency range thereto.

2. A testing system comprising a plurality of lines used for signaling communication, a 130

source of fluctuating testing current having a certain frequency range, means to develop signaling currents for transmission over the lines having a frequency range exclusive of that of the testing current, an electroresponsive test observing device, an electrical circuit connection to associate the device with the lines to be tested, and an electrical frequency filter included in such connection operable to prevent the transmission of currents within the signaling frequency range to the device while permitting the transmission of currents within the testing frequency range thereto.

15 3. A testing system comprising a plurality of lines used for signaling communication, a source of fluctuating testing current having a certain frequency range, means to develop signaling currents for transmission over the lines having a frequency range in excess of that of the testing current, an electroresponsive test observing device, an electrical circuit connection to associate the device with the lines to be tested, and an electrical frequency filter included in such connection operable to prevent the transmission of current frequencies in excess of the frequency range of the testing current to the device while permitting the transmission of currents within the testing frequency range thereto.

4. A testing system comprising a plurality of lines used for telephonic communication, a source of fluctuating testing current having a certain frequency range, means to develop telephonic currents for transmission over the lines having a frequency range exclusive of that of the testing current, an electroresponsive test observing device, an electrical circuit connection to associate the device with the lines to be tested, and an electrical frequency filter included in such connection operable to prevent the transmission of currents within the telephonic frequency range to the device while permitting the transmission of currents within the testing frequency range thereto.

5. A testing system comprising a plurality of lines used for signaling communication, a source of fluctuating testing current having a certain frequency range, means to develop fluctuating signaling currents for transmission over the lines having a frequency range exclusive of that of the testing current, means to selectively supply testing current to the lines, an electroresponsive test observing device, an electrical circuit connection for electrically associating the device and the lines, means to selectively associate such connection with the lines, and an electrical frequency filter included in such connection operable to prevent the transmission of current within the signaling frequency range to the device while permitting transmission of

currents within the testing frequency range thereto.

6. A testing system comprising a plurality of subscribers' stations, a plurality of link circuits common to the stations and individually operable to establish a telephonic circuit between two of the subscribers' stations, a source of fluctuating testing current having a certain frequency range, means in a telephonic circuit thus established to develop fluctuating telephonic currents having a frequency range exclusive of that of the testing current, means to selectively apply said testing current to the link circuits, an electroresponsive test observing device, an electrical circuit connection for associating the device and the link circuits, means to selectively associate such connection with the link circuits, and an electrical frequency filter in such connection operable to prevent the transmission of currents within the telephonic frequency range to the device.

7. A testing system comprising a plurality of adjacent lines used for signaling communication, a source of fluctuating testing current having a certain frequency range and of such low current value as to be without substantial inductive effect on lines adjacent to a line to which the testing current is applied, means to selectively apply the source of testing current to the lines, means to develop signaling current for transmission over the lines having a frequency range exclusive of that of the testing current, an electroresponsive test observing device, an electrical circuit connection to selectively associate the device with the lines, an electrical frequency filter operable to prevent the transmission of currents within the signaling frequency range while permitting the transmission of currents within the testing frequency range, and a current amplifier, the filter and the amplifier being both included in the circuit connection and the amplifier serving to supply amplified testing current to the test observing device.

8. A testing system comprising a plurality of adjacent lines used for signaling communication, a source of testing current of such low current value as to be without substantial inductive effect upon lines adjacent a line to which said testing current is applied, means to connect the source of testing current with any desired one of the lines, an electroresponsive test observing device, an electrical circuit connection to individually associate the device with the lines, and a current amplifier in the connection to supply amplified testing current to the test observing device upon association of the connec-

- tion with a line to which the source of testing current is connected.
9. A testing system comprising a plurality of subscribers' stations, a plurality of adjacent link circuits common to the stations and individually operable to establish a telephonic circuit between two of the subscribers' stations, a source of testing current of such low current value as to be without substantial inductive effect upon link circuits adjacent a link circuit to which such testing current is applied, means to connect the source of testing current with any desired one of the link circuits, an electroresponsive test observing device, an electrical circuit connection to individually associate the device with the link circuits, and an electrical current amplifier in the connection to supply amplified testing current to the testing observing device upon association of the connection with the line to which the source of testing current is connected.
10. A testing system comprising a source of fluctuating testing current having a certain frequency range, a plurality of lines used for the transmission of a current frequency exclusive of that of the testing current, an electroresponsive test observing device, an electrical circuit connection to associate the device with lines to be tested, an electrical frequency filter included in such connection operable to prevent the transmission of currents of the last named frequency to the device while permitting the transmission of currents within the testing frequency thereto, and means to amplify the currents within the testing frequency.
11. A testing system comprising a plurality of adjacent lines used for signaling communication, a source of testing current, a test observing device, an electrical circuit connection to selectively associate the device with said lines, a filter operable to prevent the transmission of currents other than those within the testing range, and a current amplifier, the filter and the amplifier being both included in the circuit connection and the amplifier serving to supply amplified testing current to the test observing device.
12. A testing system comprising a plurality of subscribers' lines, a plurality of link circuits common to said lines and operable to establish connection between two of said lines, a source of testing current, means to connect the source of testing current with any one of said link circuits, a test observing device, an electrical circuit connection to associate said device with said link circuits, and an amplifier in the connection to supply amplified testing current to the test observing device upon association of the connection with the link circuit to which the source of testing current is connected.
13. In an electrical testing system, telephone lines, means for transmitting talking current over said lines, means for applying a testing current of low current value to said lines, a detecting circuit including a filter for rejecting said talking current and admitting said testing current and including means for subsequently amplifying said testing current, and electroresponsive apparatus for detecting said amplified current.
14. In an electrical testing system, telephone lines, means for transmitting talking current over said lines, means for applying a testing current of low value to said lines, a detecting circuit including a filter for rejecting said talking current and admitting said testing current and including a vacuum amplifier for increasing the strength of said testing current, and a telephone receiver for detecting said amplified testing current.
15. In an electrical testing system for telephone lines, a plurality of lines, means for transmitting telephonic current over said lines, means for applying a testing current of low value to said lines while telephonic current is being transmitted thereto, means for subsequently amplifying said testing current, a detecting circuit including a filter for rejecting said telephonic current and admitting said testing current, and electroresponsive apparatus for detecting said amplified testing current.

In witness whereof, I hereunto subscribe my name this 13th day of January A. D. 1920.

KENNETH S. JOHNSON.
